UNITED STATES PATENT OFFICE.

JOHN B. HOLMES, JR., OF NEW YORK, N. Y.

RATCHET-PULLEY FOR BLIND-CORDS.

Specification of Letters Patent No. 26,433, dated December 13, 1859.

To all whom it may concern:

Be it known that I, JOHN B. HOLMES, Jr., of the city, county, and State of New York, have invented, made, and applied to use a 5 certain new and useful Improvement in Ratchet-Pulleys for Blind-Cords; and I do hereby declare that the following is a full, clear, and exact description of the construction and operation of the same, reference being had to the annexed drawing, making 10 part of this specification, wherein—

Figure 1, is an elevation of my ratchet rack; Fig. 2 is a side view of the same, and Fig. 3 is a section of the roller and bridle pawl taking the rack.

Similar letters denote the same parts.

The ratchet racks taking the blind cord that have heretofore been used, have been mostly formed either by two wedges set in 20 slides, or else by a spring pawl taking a ratchet. In the first instance the wedges occupy so much room that but little movement is obtained compared to the length of the slides holding such wedges, beside which the 25 wedges often become so tight that difficulty exists in separating them and releasing the tension of the blind cord: In the latter instance the spring pawl and pulley have to be slid out from the bottom end and reentered at the top in order to lessen or vary 30 the tension on the blind cord.

My said invention obviates all the difficulties before mentioned and consists in a ratchet rack projecting slightly from the 35 window casing and with the teeth on the back thereof taking a bridle pawl that passes around and receives the roller for the blind cord, thereby the ratchet teeth are kept almost out of sight, and the bridle and pulley 40 can be slid in either direction the entire length of the ratchet. My ratchet pulley is thus more available than other fixtures, and is reliable, durable and neat.

In the drawing *a* is a metal bar bent or 45 formed at the ends so as to be attached by the screws or nails 1, 1. 2, 2 are rack teeth on the back of this bar taking the cross

piece 3, of the bridle pawl *b*, on which the pin 4, projects and form the axis for a porcelain roller *d*, that receives the blind cord. 50 It will now be seen that the blind cord pulling upward throws the cross piece 3, into the teeth 2, and thereby the bridle and pulley are effectually retained in place, and the pulley can be slid down until the cord has 55 sufficient tension. If the cord is to be taken off or the tension lessened, the pulley can be slid up by pressing upon the lower part of the roller *d*, and drawing the upper part outward, which throws the cross piece 3, clear of the teeth 2, and leaves the whole free to slide up or down. I have shown at *c*, a spring which may be used when desired to keep the cross piece 3, toward the teeth 2.

By the use of my porcelain knob *d*, on the 65 pin 4, I form a durable, handsome and reliable roller for the cord which is far better than the cast or sheet metal rollers, and will be much more ornamental and not liable to injure the cord, and the cap or head usually 70 placed in front of the roller is dispensed with.

I do not claim a box having teeth on the back thereof or in the upper and inner side of said box; neither do I claim a porcelain 75 knob taking the cord, in itself, but

What I claim and desire to secure by Letters Patent is—

1. The metallic bar *a*, projecting from the window casing and having teeth on the back 80 thereof, in combination with the bridle pawl *b*, passing around said bar *a*, and carrying the pulley for the cord as set forth.

2. I also claim the porcelain roller *d*, on the center pin 4, in combination with the 85 bridle pawl *b*, and bar *a*, substantially as set forth.

In witness whereof I have hereunto set my signature this ninth day of November 1859.

J. B. HOLMES, JR.
